UNITED STATES PATENT OFFICE.

WILLIAM C. MORRISON, OF SMETHPORT, PENNSYLVANIA.

DESIGN FOR A TILE.

SPECIFICATION forming part of Design No. 32,612, dated May 1, 1900.

Application filed April 6, 1900. Serial No. 11,902. Term of patent 14 years.

To all whom it may concern:

Be it known that I, WILLIAM C. MORRISON, a citizen of the United States, and a resident of Smethport, in the county of McKean and State of Pennsylvania, have invented and produced a new and original Design for a Tile, of which the following is a full, clear, and exact description.

Reference is to be had to the accompanying drawings, forming a part of this specification, in which similar characters of reference indicate corresponding parts in both the views.

Figure 1 is a perspective view of a tile, showing my design; and Fig. 2 is a side elevation of the same.

The design in its entirety consists of a square head A, from which depends a truncated inverted pyramidal foot B, the base of which joins the under side of the head and the opposite sides of the pyramidal foot be-

ing formed with recesses C C', extending parallel to the base and segmental in cross-section, as is plainly indicated in the drawings.

The leading feature of the design consists of the head, the pyramidal foot depending invertedly from the head and appearing with recesses in opposite sides. 25

Having thus fully described my invention, I claim as new and desire to secure by Letters Patent— 30

The design for a tile, as herein shown and described.

In testimony whereof I have signed my name to this specification in the presence of two subscribing witnesses.

WILLIAM C. MORRISON.
